UNITED STATES PATENT OFFICE

HENRY J. STUART, OF NEW HAVEN, CONNECTICUT

HOSE SUPPORTER BUTTON

Application filed May 1, 1931. Serial No. 534,194.

This invention relates to garment supporters and has particular relation to buttons for hose supporters and the like.

An object of the invention is to provide an improved construction of supporter wherein the means for clamping the hose or other article is so constructed and of such material that there will be no cutting of threads to result in runs in hose.

10 A more specific object is to provide a supporter having the characteristics stated and which includes a button and loop, the button including a head and a shank the shank being of soft compressible material as for example 15 felt, and being of substantially the same size or diameter as the head, and the distance between the side or clamping arms of the loop being slightly less than the diameter of the shank whereby the loop will form a head for 20 the button by depressing a portion of the shank at each of its sides where it is engaged by the arms of the loop.

Other objects and advantages will become apparent from a consideration of the following detailed description taken in connection with the accompanying drawings wherein there is shown a satisfactory embodiment of the invention. However, it will be understood that the invention is not limited to the 30 details shown but comprehends all such changes and modifications as fall within the scope of the appended claims to which reference is to be had for a definition of the invention claimed.

35 In the drawings:

Fig. 1 is a plan view of the improved supporter on an enlarged scale including the button and loop, the loop being shown in clamping position on the button;

40 Fig. 2 is a sectional view on the line 2—2 of Fig. 1 the parts being shown as when clamping a hose; and on a still more enlarged scale than Fig. 1.

Fig. 3 is a disassembled view partly in elevation and partly in section of the stud and showing the shank and base in elevation; and

Fig. 4 is a view partly in section and partly in elevation showing the improved button assembled.

50 Referring in detail to the drawings the im-

proved supporter as shown includes a button generally indicated at 5 and a loop adapted to co-operate with the button and formed of metal and generally indicated at 6.

As herein disclosed the loop 6 is pivotally connected at 7 to an anchoring portion or eye 8 and the loop includes a strengthening or cross bar 9 and slide arms 10 which are spread apart somewhat adjacent the bar 9 whereby to provide a relatively large entrance opening or eye 11 for the button.

The button 5 includes a metallic base plate 12 through which a strip of fabric or tape 13 is threaded. This fabric 13 is also looped over the pivotal connection 7 and serves as a means for connecting the button with the loop whereby a complete supporter is provided.

In addition to the base 12 the button includes a rivet or stud 14 reduced at its lower end as at 15 and having a relatively large flat head 16. Preferably, this head 16 is covered whereby there is no portion of it exposed, to come in contact with a stocking. In the drawings the head 16 is shown as covered with rubber or other protective material 17.

The stud 14 is adapted to be secured or riveted to the base 12 and the reduced end 15 of the stud is passed through the base and riveted over or upset as at 18 whereby the base and stud are rigidly connected together. Surrounding the stem of the stud is a shank 19 for the button and the shank as shown comprises a relatively thick layer of felt of substantially the same diameter as the covered head of the stud. That is, the diameter of the shank 19 is the same as, or substantially the same as, the diameter of the rubber covering 17 of the head 16 of the stud.

From the foregoing it will be seen that a thick pad is provided between the stem of the stud 14 and the arms 10 of the loop. This is due to the fact that the shank 19 is of substantially the same diameter as the diameter of the covered head of the stud. Therefore, there is considerable stock of the felt to provide a real cushion effect under the loop and there is little if any likelihood of a thread being cut. This stock also tends to maintain the size and shape of the shank indefinitely.

and has more resiliency than would less stock.

The head itself has no clamping action and serves to spread the hose or other garment being supported as clearly shown in Fig. 2. The diameter of the shank 19 is somewhat greater than the distance between the arms 10 of the loop and the loop will therefore form its own head by depressing a portion 10 of the felt shank. Thus for example, the loop may be only about .025 of an inch narrower than the diameter of the felt shank.

Owing to this structure the loop compresses the sides of the shank somewhat 15 forming its own head. This action is clearly shown in Fig. 2 wherein the supporter is shown in the act of clamping a hose 20 spread over the head of the button. In this figure it will be seen that the arms 10 of the loop 20 have pressed inwardly into the shank 19 below the covered head of the button and the hose is yieldingly held between the shank and the arms of the loop. The head will prevent the loop moving upwardly or off the felt 25 shank so that the hose is properly held.

It will now be appreciated that owing to the tendency of the felt to expand or to return to its normal position there will be a 30 constant pressure on the hose between the shank 19 and the sides of the loop. Further, it will be understood that the shank being of felt it will have a holding action since its fibres will tend to assist in holding the stocking and prevent its slipping off the button.

35 In addition to the foregoing, attention is directed to the fact that the only clamping of the hose takes place between the loop and the felt shank 19 and that there is no clamping action between the loop and the head of the button. The felt will not have a tendency to become hard and unyielding due to age and use and there will therefore be little if any tendency on the part of the supporter to cut the threads of the hose. It should 40 also be noted that the button 5 is relatively flat, the drawings being greatly enlarged and the thickness of certain of the elements exaggerated, and that it will not be conspicuous when used under light clothing.

50 Having thus set forth the nature of my invention, what I claim is:

1. A hose supporter comprising a metal clamping loop including spaced arms, a button 55 comprising a base, a head, a stem connected at one end to the head and at the other end secured to the base and a shank of substantially the same diameter as the head, said head comprising a flat metal disc covered 60 with a protective material, said shank comprising a thick layer of felt surrounding the stem, said loop adapted to co-operate with the shank to clamp a garment, and the shank being of greater diameter than the distance 65 between the arms of the loop whereby the

loop will form its own head on the button by depressing portions of the shank.

2. A hose supporter comprising a loop and a button, said button including a rigid base, a stud having a stem and a rigid head, 70 a covering of yielding material enclosing said head, said stud riveted to said base with the head spaced from the base, a heavy layer of felt on the stem and forming a shank, said shank being of substantially the same 75 diameter as the covered head, said shank being clamped between the base and the head, said loop comprising a pair of spaced arms, and said shank being of greater diameter than the distance between the arms of the 80 loop whereby the loop will form its own head on the button by depressing portions of the shank.

3. A hose supporter button comprising a rigid base, a metal stud having a head and a stem riveted to the base with the head in spaced relation to the base, a covering of yielding material enclosing the head, a heavy layer of felt on the stem and forming a shank for the button, and said shank being of substantially the same diameter as the covered 90 head.

4. A hose supporter button comprising a rigid base, a metal stud including a substantially flat head and a stem, said stem riveted to the base with the head in spaced relation to the base, said head enclosed with rubber, a shank on the stem between the head and base, said shank comprising a relatively thick layer of felt, and said shank being of substantially the same diameter as the rubber 100 enclosed head.

5. A hose supporter comprising a loop and a button, said button comprising a base, a metal head spaced from the base, a metal 105 stem connected at one end to the head and at the other end to the base, a rubber cover enclosing the head, a shank of compressible resilient material surrounding the stem between the head and base and softer than the rubber covering on the head, said shank being of substantially the same diameter as the covered head, said loop including clamping spaced apart side bars, and the diameter of the shank being greater than the distance between 110 said side bars so that said bars will compress the sides of the shank when it is placed in holding position in the loop.

6. A hose supporter comprising a loop and a button, said button comprising a base, a 120 stud having a substantially rigid head and a metal stem, the end of the stem remote from the head being riveted to the base with the head in spaced relation to the base, a heavy felt disc surrounding the stem and filling the space between the head and base to form a shank for the button, said felt shank being of substantially the same diameter as the head and of softer material than the head, and said loop including clamping side bars 125 130

spaced from each other a distance less than the diameter of the head and felt shank so that when the shank is between the bars the sides of the shank are compressed and the head overlies the bars.

7. A hose supporter button comprising a base, a relatively rigid head spaced from the base, a rigid stem secured at one end to the head and at the other end to the base, and a shank of resilient yieldable material surrounding the stem and of substantially the same diameter as the head, said shank material being softer than the head whereby the shank can be compressed between the arms of a clamping loop in order to form its own head.

In testimony whereof I affix my signature.
HENRY J. STUART.
